US00D842694S

(12) **United States Design Patent** (10) **Patent No.:** **US D842,694 S**
(45) **Date of Patent:** **** Mar. 12, 2019**

(54) **PACKAGE**

- (71) Applicant: **Kimberly-Clark Worldwide, Inc.,**
Neenah, WI (US)
- (72) Inventors: **Shawn Michael Janes**, Neenah, WI
(US); **Kathleen M. Breen**, Neenah, WI
(US); **Kindra K. Bolsinger**, Cincinnati,
OH (US)
- (73) Assignee: **Kimberly-Clark Worldwide, Inc.,**
Neenah, WI (US)
- (**) Term: **15 Years**
- (21) Appl. No.: **29/634,831**
- (22) Filed: **Jan. 25, 2018**

Related U.S. Application Data

- (62) Division of application No. 29/589,150, filed on Dec.
28, 2016, now Pat. No. Des. 812,466.

Primary Examiner — Vy N Koenig

(74) *Attorney, Agent, or Firm* — Kimberly-Clark
Worldwide, Inc.

(57) **CLAIM**

The ornamental design for a package, as shown and
described.

DESCRIPTION

FIG. 1 is a perspective view of a package showing our new
design;

FIG. 2 is a front view of the package of FIG. 1;

FIG. 3 is a back view of the package of FIG. 1;

FIG. 4 is a first side view of the package of FIG. 1;

FIG. 5 is a second side view of the package of FIG. 1;

FIG. 6 is a top view of the package of FIG. 1; and,

FIG. 7 is a bottom view of the package of FIG. 1.

In the drawings, the evenly spaced broken lines represent
environmental structure and form no part of the claimed
design; the dash-dot-dot-dash broken lines represent bound-
aries of the claimed design and form no part of the claimed
design.

1 Claim, 6 Drawing Sheets
